[57] CLAIM

The ornamental design for twin beam map light for vehicles, as shown and described.

DESCRIPTION

FIG. 1 is a top, front, left side perspective view of a twin beam map light for vehicles showing our new design;

FIG. 2 is a fragmentary front elevational view thereof on an enlarged scale;

FIG. 3 is a fragmentary right side elevational view thereof on an enlarged scale;

FIG. 4 is a top plan view thereof on an enlarged scale;

FIG. 5 is a fragmentary rear elevational view thereof on an enlarged scale;

FIG. 6 is a fragmentary left side elevational view thereof on an enlarged scale; and

FIG. 7 is a fragmentary bottom plan view thereof on an enlarged scale.

The flexible cable is fragmentarily shown and the plug omitted in FIGS. 2, 3, 5, and 7 for convenience of illustration. The flexible cable is also broken away in FIG. 6 for convenience of illustration.
